UNITED STATES PATENT OFFICE.

ABRAM ALBERT WEAVER AND JOHN WILLIAM BROOKS, OF WARRENSBURG, MISSOURI.

STATION CALL AND SIGNAL.

SPECIFICATION forming part of Letters Patent No. 449,505, dated March 31, 1891.

Application filed November 8, 1890. Serial No. 370,788. (No model.)

To all whom it may concern:

Be it known that we, ABRAM ALBERT WEAVER and JOHN WILLIAM BROOKS, citizens of the United States, residing at Warrensburg, in the county of Johnson and State of Missouri, have invented certain new and useful Improvements in Station Calls and Signals; and we do hereby declare the following to be a full, clear, and exact description of the invention, such as will enable others skilled in the art to which it appertains to make and use the same.

This invention relates to station-indicators, and has for its object to simplify the operating mechanism for operating the name-strip and at the same time releasing the alarm mechanism, whereby attention is called to the device.

The improvement consists of the novel features and the peculiar construction and combination of the parts which will be herein-after more fully described and claimed, and which are shown in the annexed drawings, in which—

Figure 1 is a front view of an indicator embodying my invention. Fig. 2 is a cross-section of the name-strip, the spools on which the said strip is wound, the shafts for the spools, and the guide-rollers about on the line 2 2 of Fig. 1, looking to the left. Fig. 3 is a cross-section on the line 3 3 of Fig. 1 in front of the operating-disk-returning spring, looking to the left, showing the trip-bar, the brake mechanism, the operating-disk, and the returning-spring. Fig. 4 is a cross-section on the line 4 4 of Fig. 1 just inside of the operating-disk, showing the ratchet-wheel on the winding-shaft, the pawl for operating the same, and the brake mechanism. Fig. 5 is a cross-section on the said line 4 4 just inside of the operating-disk, looking to the right. Fig. 6 is a perspective view showing the case opened. Fig. 7 is a detail perspective view showing the means for locking the spools on their shafts. Fig. 8 is a detail perspective view of the scape-wheel, the pallet, and the releasing mechanism. Fig. 9 is a bottom plan view showing the relation of the releasing mechanism to the pallet and the scape-wheel. Fig. 10 is a detail perspective view of the arm for engaging the pallet and bearing on the scape-wheel. Fig. 11 is a front

view of the movement, showing the relative arrangement of the releasing mechanism and the operation of the same by dotted lines.

The case is of suitable construction to contain the operating parts of the indicator and is composed of the back A, bottom B, ends C and D, top E, and front or door F, the latter having an opening through which the name-strip is seen, the said opening being protected by glass. The guide-rollers H and H' and the shafts G and G' are journaled at their ends in the end pieces D and C and between their ends in the partition I, which is parallel with and but a short distance from the end C. 55 The spools g and g', on which the name-strip J is wound, are mounted on the shafts G and G', respectively, and have notches g² in their ends, which receive a cross-pin g³ in each of the shafts, by means of which the spools are 60 made fast to and caused to revolve with the said shafts. Each of the shafts is provided with a brake-wheel, the brake-wheel K being on the shaft G and the brake-wheel K' on the shaft G'. 65

The brake-shoes k and k' operate on the brake-wheels K and K', respectively, and are caused to press thereon by means of the connecting-spring k². The ratchet-wheel k³ is formed on the side of the brake-wheel K' 70 and is operated on by the pawl k⁴, which is pivoted on the disk L, that is mounted loosely on the shaft G, so as to turn freely thereon. The returning-spring l is secured at one end to a post and at its other end to the disk L 75 and serves to return the said disk to a normal or starting point. The operating-cord M is connected with the disk L.

The alarm N comprises a gong-bell and the usual train of gearing for operating the hammer. 80

O represents the scape-wheel of the movement, and P the pallet of well-known construction and operation. The releasing-rod Q has an endwise movement and is provided with 85 an arm q, which projects at right angles therefrom, and which is recessed in its side to embrace the pallet and prevent its operation. This arm q also bears on the scape-wheel and acts in the capacity of a brake-shoe. The 90 spring q' acts on the rod Q and holds the arm q in engagement with the pallet and with the 95

scape-wheel. The alarm is secured on the door F, and the rod Q projects through the door and comes in contact with the bar R, which latter is acted on by the projection S on the disk L when the latter is operated.

5 The operation of the invention is as follows: A pull on the cord M rotates the disk L, and by means of the pawl k^4 and the ratchet-wheel k^3 rotates the shaft G and winds the 10 name-strip thereon. At the same time the projection S on the disk L strikes the bar R and pushes the bar Q in in such a manner as to disengage the arm q thereof from the pallet and the scape-wheel to permit the sounding 15 of the alarm. On releasing the cord the spring l will carry the disk back to its normal position, and the spring q' will press the arm q in engagement with the scape-wheel and the pallet. When the name-strip is wound from 20 the roller g' onto the roller g and the car or vehicle is in position for the return trip, the end D, door F, and top E are opened about as shown in Fig. 7, and the spools g and g' are removed from the shafts G and G' and 25 replaced thereon in reverse order—that is, the spool g, which was on the shaft G, is now placed on the shaft G', and the spool g' is placed on the shaft G, the spool g' being empty and the spool g having the name-strip wound thereon.

30 Obviously the names are printed on both sides of the strip, but in reverse order. By this arrangement the rewinding of the strip at the termini of the route or the shifting of the mechanism is obviated and the device 35 proportionally simplified.

Having thus described our invention, what we claim, and desire to secure by Letters Patent, is—

40 1. In a station-indicator, the combination, with the name-strip and the name-strip-oper-

ating mechanism, of an alarm and a releasing device to be operated on by the name-strip-operating mechanism and provided with an arm which operates on the escapement of the alarm-movement, substantially as described. 45

2. In a station-indicator, the combination, with the name-strip and name-strip-operating mechanism, of the alarm, the rod Q, having an arm to engage with the escapement of the alarm-movement, and the bar R, in contact 50 with the rod Q and adapted to be operated on by the name-strip-operating mechanism, substantially as described, for the purpose specified.

3. In a station-indicator, the combination, 55 with the shafts and means for operating one of the shafts, of a name-strip having the names printed on both sides thereof and rollers having the ends of the name-strip connected therewith and adapted to be slipped on or off the 60 said shafts and adapted to be fastened to the said shafts, so as to revolve therewith, substantially as set forth.

4. In a station-indicator, the combination 65 of the shafts G and G', mechanism for operating shaft G, the removable spool adapted to be held on the said shafts to turn therewith, the name-strip printed on both sides, the brake-wheels on the shafts, and the brake-shoes connected and caused to press upon the 70 brake-wheels by a spring, substantially as set forth.

In testimony whereof we affix our signatures in presence of two witnesses.

ABRAM ALBERT WEAVER.
JOHN WILLIAM BROOKS.
